DESIGN FOR A TIMER CASE

Belle Kogan, New York, N. Y., assignor to Warren
Telechron Company, a corporation of Massachusetts

Application September 25, 1935, Serial No. 58,692

Term of patent 14 years

To all whom it may concern:

Be it known that I, Belle Kogan, a citizen of the United States, residing at New York, in the county of New York, State of New York, whose post-office address is 185 Madison Avenue, New York, N. Y., have invented a new, original, and ornamental Design for a Timer Case, of which the following is a specification, reference being had to the accompanying drawing, forming a part thereof. The figure is a front perspective view of a timer case showing my new design.

I claim:

The ornamental design for a timer case as shown.

In witness whereof, I have hereunto set my hand this 14th day of September, 1935.

BELLE KOGAN.
